BAG MACHINE

Howard H. Orr, Cleveland, Ohio, assignor to The
Jaite Company, Jaite, Ohio, a corporation of
Ohio

Application December 30, 1937, Serial No. 182,449

5 Claims. (Cl. 93—8)

My present invention relates to the manufacture of open mouth gusseted bags and, particularly, although not necessarily, to the manufacture of relatively large heavy-duty shipping bags 5 of the type adapted to contain up to 100 pounds or more of materials of various types.

Shipping bags of the type discussed above may be formed from paper tubes or blanks of desired size cut from a tube of indeterminant length 10 and may comprise one or a plurality of plies. Gussets are formed by flattening the tube and folding the edges thereof inwardly. The bottom of the bag may be closed by a line of stitches extending through the gussets. Preferably, the 15 bag is provided with a strip of adherent material, such as gummed crepe paper, extending along the line of stitches and folded over the end of the bag to prevent sifting of the contents of the bag through the stitches. This strip of adherent material may be applied to the bag either before or 20 after the line of stitches is formed therein.

It will be understood from the foregoing, that the material from which a bag is to be formed passes through various stages during the process 25 of manufacture. In the following description, the word "tube" is used generically to define the material at any stage of manufacture after the blanks of predetermined size have been cut from the continuous tube. Thus, the word "tube" refers to a completed bag as well as to an incomplete bag at any stage of manufacture.

In Patent No. 2,017,838, granted October 22, 1935, to W. N. Baker, et al., there is disclosed a bag of the type described above wherein means is 35 provided to prevent the disarrangement of the gussets in the open mouth of the bag during the filling thereof. A preferred form of means for this purpose comprises fastening means passing through the body of the bag and the gussets 40 and located adjacent to and on each side of the open mouth of the bag. Since these fastening means must be accurately and unfailingly applied to the bag in the location contemplated in said Patent No. 2,017,838, it has heretofore been necessary to apply the fastening means in a separate, time-consuming operation, performed either before or after the bottoming operation, which materially increases the cost of manufacture of the bags. For example, one method which has been 45 employed involves the manual insertion of the gusseted paper tubes into a stapling machine for the application of the gusset fastening means.

It is an object of my invention to provide a bag machine in which the operation of fastening the gussets at the unclosed end of a paper

tube may be performed during the substantially uninterrupted progress of the tube through the machine.

It is a further object of my invention to provide a bag machine in which the operations of bottoming at one end and gusset fastening at the other end of a paper tube may be performed concurrently, or in rapid succession, during the substantially uninterrupted progress of the tubes through the machine.

It is a further object of my invention to provide means whereby fastening devices may be accurately placed at predetermined points on each of a series of continuously moving objects.

In accordance with my invention, gusset holding means are applied to the gusseted marginal portions adjacent that end of a paper tube which is to constitute the open mouth of a completed bag by means such as an intermittently operable stapling machine. In order that this operation may be carried out while the tubes are moving upon a conveyor, it is necessary to time the intermittent operation of the stapling machine with the progress and spacing of the tubes upon the conveyor. It will be appreciated that the gusseted marginal portions of a tube are spaced from each other by a distance substantially equal to the entire width of the tube. When a series of such tubes is conveyed through a bag bottoming machine, for example, the conveyor is so arranged that the marginal edges of successive tubes within the series are spaced at a minimum distance in order that the operation of bottoming may be performed rapidly and economically. Thus, the operation of a stapling machine, for the application of staples in the margins of a series of tubes upon a conveyor of the type normally provided in a bottoming machine, must be timed to apply a staple in the leading marginal edge of a tube and remain inoperative for the substantial period of time consumed by the progress of the conveyor through a distance substantially equal to the width of the tube. The stapling machine must then be operated to apply a staple to the trailing marginal edge of the tube. The stapling machine must then remain inoperative for the short period of time consumed by the movement of the conveyor through the distance represented by the spacing between successive tubes. At the end of this time, the leading edge of the next tube within the series will be in position to receive a staple. It is, therefore, a more specific object of my invention to provide means for automatically timing the op-

eration of a stapling machine with the movement of a conveyor in the above manner.

My invention has for other and further objects, such advantages in operation and use as will become more apparent upon a consideration of the following description of a preferred but not necessarily the only form of my invention, together with the drawings accompanying and forming a part of this specification.

10 In the drawings,

Fig. 1 is a top plan view of a machine embodying my invention;

Fig. 2 is a side elevational view of the same;

Fig. 3 is an end elevational view of the same looking toward the left as viewed in Figs. 1 and 2;

Fig. 4 is a detail view of a part of the machine shown in Fig. 1; and

Figs. 5 to 8 inclusive are progressive diagrammatic illustrations of the operation of the machine.

Referring now to the drawings in which similar characters of reference refer to similar parts throughout the several views, the machine comprises a main frame 10 upon which the various elements of my novel combination may be conveniently supported.

A motor M is supported in the frame 10 and is controlled by a switch box S provided with an actuating treadle T brought out to a convenient location in order that the operation of the motor may be controlled at will.

The rotatable shaft of the motor M is provided with a sprocket wheel 11. A sprocket chain 12 extends over the wheel 11 and a sprocket wheel 13 carried by a shaft 14 supported in the main frame 10 for rotation in suitable bearings (not shown). The shaft 14 carries a gear 15 which meshes with a gear 16 carried by a shaft 17 mounted in suitable rotary bearings (not shown).

40 The shaft 17 has fixed thereon a sprocket wheel 18 which through a chain 19 rotates a sprocket wheel 20 carried by a shaft 21 suitably supported in the main frame. The shaft 21 has fixed thereupon a sprocket wheel 22 which through a sprocket chain 23 drives a sprocket wheel 24 fixed upon a shaft 25. The shaft 25 carries sprocket wheels 26 and 27. The sprockets 26 and 27 serve to support and drive a conveyor comprising belts 28 and 29.

50 The belts 28 and 29 are continuous and are supported at the opposite end of the machine upon sprockets 30 and 31 carried by an idler shaft 32 mounted for free rotation in the main frame of the machine.

55 The conveyor belts 28 and 29 may comprise a plurality of articulated separable sections 33, as shown in Figure 2. Certain of these sections may be provided with cleats 34 which serve to advance paper tubes placed upon the conveyor. It will be understood that it may be desired to form bags from paper tubes of various widths. It is desirable to space the tubes upon the conveyor at a minimum distance for reasons which will more clearly appear hereinafter. To this end, the number of sections 33 lying between successive cleated sections may be varied by the simple expedient of removing certain of the sections or adding a desired number of such sections. As shown in Figure 2, the over-all length

70 of the belts 28 and 29 may be greater than that necessary to encompass the sprockets 26, 30 and 27, 31 and minor variations in over-all length which may be caused by the addition of sections 33 or removal of such sections will result merely in altering the amount of slack existing in the lower reach of the belts 28 and 29 as they ex-

tend between their respective sprockets. As shown in Figs. 1 and 3, a plate 107 is supported on the main frame 10. This plate is slotted as at 107' to allow the articulating members 33' to depend through the plate while the ends of 5 the sections 33 rest upon the plate. The upper reaches of the conveyor belts 28, 29 are thus supported in a horizontal plane. While the plate 107 preferably extends substantially over the entire upper surface of the machine, it has been 10 broken away in Fig. 1 to avoid complication of the drawing. It will be understood that the plate 107 is supported in any convenient manner and is provided with suitable apertures for the operation of the various elements of the machine. 15

The shaft 14 is extended to the right, as seen in Figure 3, and forms a drive shaft for a sewing machine of any desirable type, which is indicated generally by the reference character 35. The shaft 14 carries a gear 36 which meshes 20 with a gear 37 within the sewing machine and which serves to actuate the sewing machine. The stitching mechanism of the sewing machine 35 operates continuously and is so located relative to the conveyor 28, 29 that it forms a continuous line of stitches passing successively through the ends of a series of paper tubes carried by the conveyor.

The shaft 25 also carries a sprocket wheel 38 which through a chain 39 and sprocket wheel 40 30 imparts rotation to a stub shaft 41 for rotation in the main frame 10. The shaft 41 carries an eccentric cam 42. A cam follower 43 is carried at one end of a two-armed lever 44 which is pivoted at 45 to the main frame 10. Rotation of 35 the cam 42 serves to rock the lever 44 about its pivot 45 and to impart a reciprocatory motion to the end 46 of the lever 44. The end 46 carries a pawl 47 which cooperates with a notched wheel 48. It will thus be seen that 40 rocking of the lever 44 will produce a step by step rotation of the ratchet wheel 48. The ratchet wheel 48 imparts its step by step rotation to a rotary shear member 49. The ratio 45 between the sprocket wheels 38 and 40 and the convolution of the cam 42 is so chosen that the shear member 49 will be caused to sever the line of stitches extending between successive bags of a series carried by the conveyor 28, 29.

If so desired, a tape 50 may be folded over the 50 end of the tube prior to the stitching operation. The tape 50 may be provided with an adhesive material to secure the same to the tube, if so desired. Thus, a supply reel 51 may be mounted in any convenient manner upon the main frame 55 10 and the tape 50 may be conducted from the reel 51 to a guide plate 52 and into a folding channel 53. It will be understood that the tape 50 is folded in the channel 53 into a trough-like shape to serve as a seal for the bottoms of the 60 bags on the conveyor. The shear 49 will sever the tape 50 within the space between successive bags carried by the conveyor 28, 29.

A pair of pressure rolls 54, 55 may be provided to press the tape 50 into contact with the tube 65 after the tape 50 has been stitched to the tube. The rolls 54 and 55 may be supported in any convenient manner.

A pair of flattening rolls 56, 57 may be driven at a surface speed equal to that of the conveyor 70 28 and 29. To this end the shaft 32 carries a sprocket 58 which through a chain 59 imparts rotation to a sprocket wheel 60. The sprocket wheel 60 is mounted upon a suitable rotatable stub shaft 61 which has fixed thereto the lower flattening roll 57. The shaft 61 also has fixed 75

thereto a pinion 62 which meshes with a pinion 63 carried by stub shaft 64. The stub shaft 64 also carries a sprocket 65 which through a chain 66 imparts rotation to a sprocket wheel 67 carried by a stub shaft 68. The stub shaft 68 has fixed thereto the upper flattening roll 56.

The structure so far described is conventional and for further details thereof reference is here made to patent to Orr, 1,926,241, dated September 12, 1933 and patent to Wechsler, 1,749,118, dated March 4, 1930.

The operation of the mechanism thus far described will now be set forth. The upper reach of the conveyor 28 and 29 is constantly driven by the motor M in the direction of the arrows in Figure 1. Gusseted paper tubes open at both ends are placed successively upon the conveyor 28, 29 in contact with the cleats 34 thereon. One end of each paper tube may be gauged against a gauge plate 69 and supported upon the upper surface of the plate 107 and frame member 10'. The gauge plate 69 is in effect a continuation of the guide plate 52 and channel 53, above described. The tubes are progressed through the flattening rolls 56, 57 and to the tape-applying section of the machine. The tape 50 is folded over an open end of each tube and the taped tubes are then progressed to the sewing head 35. The tubes are progressed through the sewing head 30 and a line of stitches is placed through the tape and the end of the tube to form the bottom of a bag. The bottomed tubes then progress through the pressure rolls 54, 55 in the form of a continuous series of tubes interconnected by lines of stitching and tape. As the series is progressed past the shear 49, the shear operates in such timed relation as to sever the lines of stitching and tape at points intermediate successive tubes within the series.

According to my invention, a fastener-applying means is mounted upon the main frame 10 in such a position that it may apply fasteners in the gusseted areas of the ends of the paper tubes opposite to those in which the bottom is formed by the mechanism above described. While fastener-applying devices of various types may be employed in embodiments of my invention, I have chosen for purposes of illustration to describe an embodiment of my invention in which a stapling machine of the type adapted to form and apply wire staples is employed.

In general, the stapling machine includes a stapling head 70 and an anvil 71. A supply of wire 72 is mounted upon the stapling head and individual staples are cut and formed from the supply 72 and are applied to objects placed between the head and anvil. For the operation of this stapling device there is provided a continuously operating motor 73 and a single revolution clutch 74. The single revolution clutch 74 is normally maintained in inoperative condition by a spring pressed slide 75. When the slide 75 is pulled downwardly against its spring the clutch 74 is released to connect the motor with the stapling device for the formation and application of a single staple. A two-armed lever 76 is pivoted at 77 to the lower part of the stapling head. One end of the lever 76 is pivotally connected at 78 to the slide 75. The opposite end 79 of the lever 76 is therefore in the nature of a trigger and upward movement of the end 79 will result in release of the single revolution clutch and operation of the stapling device.

According to my invention, the stapling device thus far described is mounted upon a bracket

80 attached to the main frame 10 of the bag machine. The stapling head extends into the path of travel of the paper tubes passing through the bag machine and the end 79 of the lever 76 extends into the machine below said path. The 5 stapling device may be positioned at any convenient point along the path of the tubes as they progress through the machine. The operation of the stapling device is extremely rapid and for this reason staples may be applied to 10 the moving tubes without objectionable interference with their movement.

The end 79 of the lever 76 is provided with a roller 81 which is positioned for cooperation with a cam 82 provided with lugs 83 and 84. The cam 15 82 is mounted upon a shaft 85 rotatably mounted in the main frame 10. The following means is provided for rotating the cam 82 to present the lugs 83 and 84 to the follower 81 for actuation of the stapling device in timed relation to the 20 movement of the conveyor 28, 29. The shaft 21 has fixed thereon a pinion 86 which meshes with a gear 87 fixed upon a shaft 88. The shaft 88 also has fixed thereon a gear 89 which is adapted to mesh with one or the other of a set of gears 25 90, 91 and 92 slidably keyed upon a shaft 93. The shaft 93 is rotatably mounted in bearings 94 and 95. The bearings 94 and 95 are adjustably mounted upon the frame 10 for sliding movement limited by slots 96 (see Fig. 1). The 30 slots 96 are adapted to receive studs 97 which may be tightened to hold the bearings 94 and 95 in adjusted position upon the frame 10. The adjustment just described is for the purpose of moving the shaft 93 into proper position relative 35 to the shaft 88 for meshing of the gear 89 with any one of the gears 90, 91 or 92.

The shaft 93 has fixed thereon a sprocket wheel 98 which through a chain 99 imparts rotation to a sprocket wheel 100 fixed upon the 40 cam shaft 85. The chain 99 is made of sufficient length to allow for the adjustment of shaft 93 relative to the shaft 98. A weighted idler 101 is slidably carried in a slotted bracket 102 and bears upon the chain 99 to maintain the same 45 taut irrespective of the position of the shaft 93.

It will thus be seen that the cam shaft 85 may be driven at various speeds bearing fixed proportions to the speed of the conveyor 28, 29.

Since the bottoming mechanism hereinbefore 50 described operates continuously to apply a continuous line of tape and stitching to the successive tubes within a series carried by the conveyor 28, 29, it may be seen that the spacing between adjacent tubes should be at a minimum in order 55 to prevent waste of large quantities of tape and stitching material. To this end, the sections 33 and 34 of the conveyor 28, 29 may be rearranged for operation upon tubes of any particular width. The cleated sections 34 should be spaced apart 60 a distance slightly greater than the width of a single paper tube.

In order to secure the application of fasteners at proper points on each of the paper tubes carried by the conveyor 28, 29, the cam shaft 85 65 must be given one complete rotation during the time that the conveyor 28, 29 progresses a distance equal to the spacing between the cleats 34. The variable speed gear set 89, 90, 91, 92 may be adjusted as above described to secure this re- 70 suit for any given spacing of the cleats 34.

The lug 83 upon the cam 82 is positioned to contact the follower 81 to cause operation of the stapling device at the time that the gusseted trailing edge of a paper tube is in position to 75

receive a staple. The lug 84 upon the cam 82 is so located as to contact with the follower 81 to cause operation of the stapling device when the gusseted leading edge of the next paper tube within the series upon the conveyor 28, 29 is in position to receive a staple.

The lugs 83 and 84 may bear a fixed relationship to one another and be integrally formed with the cam 82. There may be relatively small variations in the width of tubes which would produce variations in spacing between the trailing edge of one tube and the leading edge of the next and such variations must be met by the substitution of other cams 82 upon which the lugs 83 and 84 are appropriately spaced. While such substitution may not be objectionable in manufacturing plants in which variations in bag width are relatively infrequent, it may be desirable to provide for adjustability of the cam 82 when frequent variations are to be expected. In Fig. 4, I have shown one form of cam in which provisions are made for adjustment.

In Fig. 4, the lug 83 is carried by a section 105 fixed to the shaft 85 as by a key 106. The lug 84 is carried by a section 103 freely rotatable upon the shaft 85 but which may be secured in desired angular position thereon as by a set screw 104. The lug 83 therefore may bear a fixed relationship to the cleats 34 for the application 30 of fasteners to the trailing edges of tubes in engagement with the cleats 34. Since the position of the leading edges of the tubes upon the conveyor will vary in accordance with the width of the tubes, the position of the lug 84 may be 35 adjusted to cause application of fasteners within the leading gusseted edges of tubes of various widths.

When the change in bag width becomes sufficiently large to require a change in spacing between cleats 34, the variable speed gear set 89, 90, 91, 92 is adjusted as above outlined. When the cam 82 is constructed as shown in Fig. 4, it may be necessary to rotate the cam shaft 85 relative to its driving means to establish the 45 proper relationship between the fixed lug 83 and the cleats 34. The adjustment of spacing between the cleats 34 is necessarily limited to increments equal to the width of the sections 33 and the ratios available in the gear set 89, 90, 50 91, 92 may bear fixed proportions to such increments in order that the cam 82 may perform a complete revolution during the progress of the conveyor 28, 29 through a distance equal to the spacing between successive cleats 34. Since the 55 change in bag width may not bear a fixed proportion to these increments the movable lug 84 may be adjusted to accurately locate the fasteners to be applied in the leading edges of the tubes.

60 It is obvious that the lug 83 may be mounted upon a movable cam section similar to the section 103. In such event, both lugs 83 and 84 may be quickly and accurately positioned for any particular arrangement of the conveyor 28, 29 and any particular width of bag.

The plate 107 serves to support the ends of the tubes which are conducted to the stapling device. The plate 107 is provided with an upturned flange 108 which serves, in conjunction 70 with the gauge 69 and guides 52, 53, to maintain the tubes in accurate alignment as they progress through the machine.

The operation of my improved bag machine will now be set forth with particular reference 75 to Figures 5 to 8 inclusive in the drawings. For

operation upon paper tubes of a predetermined width, the sections 33 of the conveyor 28, 29 are rearranged to provide an appropriate spacing between cleats 34. The gear set 89, 90, 91, 92 is adjusted to cause a single rotation of the shaft 85 5 during the progress of the conveyor through a distance equal to the spacing between successive cleats 34. A cam having lugs 83, 84 properly spaced thereon may be placed upon the shaft 85. However, according to the preferred form of my 10 invention the lugs 83 and 84 are respectively located upon relatively adjustable sections, as previously described, and the lugs 83, 84 will therefore be adjusted to cause operation of the 15 stapling machine at proper intervals. Paper tubes are placed upon the conveyor 28, 29 and are progressed thereby into the machine. When the leading gusseted edge portion 111 of the first tube within the series reaches a position between the stapling head 70 and anvil 71 the lug 84 contacts the follower 81 to cause operation of the 20 stapling head to apply a fastener 110 at the point indicated in Figure 5. In Figure 5, the 25 relative locations of the lugs 83, 84 and follower 81, which occur when the leading edge 111 is in position to receive a fastener, are diagrammatically illustrated and a fastener 110 is shown in applied position. It will be seen in Figure 5 that the tape 50 has been applied to the opposite ends of the paper tubes. As the tubes continue to 30 progress the follower 81 drops to inoperative position between the lugs 84 and 83 and the stapling head remains inoperative during the 35 progress of the tubes through the position indicated in Figure 6. It will be observed that during this period of the progress of the first paper tube within the series, the sewing head 35 may start the application of stitches incident to bottoming of the tube. When the trailing edge 113 reaches the position illustrated in Figure 7, the 40 lug 83 contacts the follower 81 to cause the application of a fastener 112 as shown in said figure. In the position illustrated in Figure 8, the first tube within the series has progressed beyond the stapling device and the leading gusseted 45 edge 115 of the succeeding tube has advanced into such a position that the lug 84 has contacted the follower 81 to cause application of a fastener 114 to the leading edge 115. It will thus be seen that I have provided means for the 50 successive application of fasteners within the gusseted areas of the open ends of a series of paper tubes during the progress thereof through a bottoming machine.

While the above detailed description has been 55 made in order to comply with statutory requirements, it is obvious that those skilled in the art may make modifications and variations in detail. The above description is therefore to be taken in an illustrative rather than in a limiting 60 sense and it is my intention to claim my invention as broadly as permissible within the legitimate scope of the appended claims.

I claim:

1. In a bag machine: a conveyor for progressing a series of flattened gusseted paper tubes; means for spacing said tubes on said conveyor; means for closing one end of each of said tubes while the same are being moved by said conveyor; intermittently operable fastener applying means 70 mounted for operation on said tubes adjacent the opposite ends thereof while the same are being moved by said conveyor; and means for causing operation of said fastener applying means synchronized with the movement and spacing of the 75

tubes on said conveyor to cause the application of fasteners to said tubes only within the area of the gussets.

2. In a bag machine: means for conveying a series of flattened paper tubes having gussets formed in their opposite edges through said machine at regularly spaced intervals; means for closing one end of each of said tubes while the same are being moved by said conveying means; and means operating in timed relation with said conveying means for applying fasteners at points adjacent to and on each side of the opposite open ends of the tubes within the area of the gussets.

3. A process for making bags comprising: progressing a series of flattened, gusseted paper tubes at uniform speed and with uniform spacing; forming a complete closure across one end of each of said tubes while the same are progressing; and securing against expansion the gussets of each of said tubes adjacent the opposite ends thereof, leaving the walls of each of said tubes intermediate said gussets unsecured, such securing being done while said tubes are being progressed.

4. A process for making bags comprising: progressing a series of flattened, gusseted paper tubes at uniform speed and with uniform spacing; forming a complete sewed closure across one end of each of said tubes while the same are progressing; and securing against expansion the gussets of each of said tubes adjacent the opposite ends thereof, leaving the walls of each of said tubes intermediate said gussets unsecured, such securing being done while said tubes are being progressed. 5

5. A process for making bags comprising: progressing a series of flattened, gusseted paper tubes at uniform speed and with uniform spacing; forming a complete closure across one end of each 15 of said tubes while the same are progressing; and stapling against expansion the gussets of each of said tubes adjacent the opposite ends thereof, leaving the walls of each of said tubes intermediate said gussets unstapled, such stapling being 20 done while said tubes are being progressed.

HOWARD H. ORR.
